CLAIM

The ornamental design for a baby play mat, as shown and described.

DESCRIPTION

FIG. 1 is a perspective view of the baby play mat showing my new design;

FIG. 2 is a perspective view thereof from another angle;

FIG. 3 is a perspective view thereof from another different angle;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the baby play mat when the adjustable base thereof is fully extended;

FIG. 11 is a partial enlarged view of portion 11 in FIG. 1;

FIG. 12 is a partial enlarged view of portion 12 in FIG. 1;

FIG. 13 is a partial enlarged view of portion 13 in FIG. 2;

FIG. 14 is a partial enlarged view of portion 14 in FIG. 2;

and,

FIG. 15 is a partial enlarged view of portion 15 in FIG. 3. The dash-dot-dash lines shown in the drawings are for the purpose of showing the area of enlargement and form no part of the claimed design.

1 Claim, 15 Drawing Sheets
